UNITED STATES PATENT OFFICE.

COLE STICKLE, OF INDIANAPOLIS, INDIANA, ASSIGNOR TO OPEN COIL HEATER & PURIFIER CO., OF INDIANAPOLIS, INDIANA.

STEAM PACKING JOINT.

Application filed September 20, 1920. Serial No. 411,655.

To all whom it may concern:

Be it known that I, COLE STICKLE, a citizen of the United States, and a resident of Indianapolis, county of Marion, and State 5 of Indiana, have invented a certain new and useful Steam Packing Joint; and I do hereby declare that the following is a full, clear, and exact description thereof, reference being had to the accompanying drawings, in 10 which like numerals refer to like parts.

This invention relates to improvements in packing boxes adaptable for use with steam heated drying cylinders for textile machines.

The particular feature of the invention 15 relates to the means for securing and supporting the siphon and vacuum valve independently of each other, and in direct communication by the nut 26 which acts as a head member mounted upon the cylinder bearing for closing the end thereof. This arrangement permits of the ready removal 20 of the siphon, head member or valve, and the position of the siphon will not be affected by the position of the valve.

Another feature of the invention lies in 25 the manner of mounting the siphon and valve in the head member, whereby each of them screw therein so that their ends abut, permitting direct communication and providing a steam-tight fitting so as to prevent 30 any leakage of steam through the end of the bearing between the head member and the siphon.

The full nature of this invention will be 35 understood from the accompanying drawings and the following description and claims.

In the drawings Fig. 1 is a central vertical cross section taken longitudinally of a 40 portion of the drying cylinder, bearing and packing box showing the vacuum valve in elevation. Fig. 2 is a central longitudinal cross section through the bearing and packing box showing an enlarged view 45 thereof. Fig. 3 is a section taken on the line 3—3 of Fig. 2. Fig. 4 is a section taken on the line 4—4 of Fig. 2.

In the drawings there is shown a drying cylinder or can of the usual construction 50 employed for drying textile and the like, said cylinder having a head 11 at each end thereof, the head 11 being provided with a hollow journal 12 for supporting the head and cylinder in the bearing 13. The bearing 55 13 is supported upon the upright supports 14

of the base 15 of the machine. Live steam is supplied to the cylinder 10 through the conduit 16 extending upwardly through the upright 14 and discharging into the bearing 13, and thence through the hollow journal 12 into the inside of the cylinder for the purpose of heating the surface thereof and drying the textile.

In order that the water accumulating within the cylinder from the condensation 65 of the steam may be removed, a siphon pipe 17 is provided having its open end in close proximity to the lower inner surface of the cylinder, and extending out through the head 11 and hollow journal 12 where it is 70 operatively connected with the vacuum valve 18 which, by reason of its construction not shown herein, will cause the water to be siphoned, or sucked from the cylinder 10.

As it has heretofore been difficult to prevent 75 the live steam, entering through the bearing and spindle, from escaping between their surfaces, a packing box is provided in the outer end of the bearing 13 whereby a tight seal may be obtained and maintained 80 by the proper adjustment thereof. The outer end of the bearing is enlarged to make room for the packing and is provided with internal screw threads adjacent its outer end. The packing material 19 is placed between 85 the bearing and journal in the enlarged portion of the former and is held therein by the packing ring and follower 20 that likewise fits between said journal and bearing and is provided with a beveled end 90 21 which is oppositely beveled from the angular surfaced shoulder 22 of the bearing.

Because of the oppositely beveled surfaces of the ring and shoulder of the enlarged portion of the bearing, between which the packing 95 material is placed, the packing material is caused to be forced inwardly against the bearing surface of the spindle by the inward pressure exerted on the ring 20. The pressure is applied to the ring follower 20 by means of the bolts 25 which screw through the nut 26. Said nut is provided with an annular flange 27 adapted to engage the end of the bearing, and external screw threads which permit the cap to be 105 screwed thereon so as to close the outer end of the bearing. As the packing 22 wears down, or if for any reason there is leakage of the steam through the bearing, by screwing up and tightening the bolts 25, they will 110

press against the side of the ring 20 and cause it to squeeze the packing inwardly against the bearing surface of the spindle by the packing, the pressure may be released by unscrewing the bolt 25 just enough to release the spindle and still prevent the escape of steam.

The invention claimed is:

1. In combination, a drying can for textile machines having a journal, a bearing for said journal through which steam may enter said can, and a vacuum valve, of a siphon adapted to extend through said journal, and a head member mounted on said bearing for supporting said vacuum valve and one end of said siphon independently

of each other, whereby said siphon and vacuum valve will be in direct communication.

2. In combination with a drying can for textile machines having a journal, a bearing for said journal through which steam may enter said can, and a vacuum valve, of a siphon adapted to extend through said journal, and a head member mounted on said bearing into which the abutting ends of said siphon and vacuum valve are adapted to screw, whereby they will be in direct communication and effect a steam-tight joint.

In witness whereof, I have hereunto affixed my signature.

COLE STICKLE.
